Primary Examiner — Clint A Samuel*(74) Attorney, Agent, or Firm* — Li & Cai Intellectual Property Office(57) **CLAIM**

The ornamental design for a projector light as shown and described.

DESCRIPTION

FIG. 1 is a front, right side, top perspective view of a projector light showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, left side, bottom perspective view thereof. The broken lines in the drawing depict portions of the projector light that form no part of the claimed design.
